UNITED STATES PATENT OFFICE

166,039

BATHTUB SAFETY MAT

Herman Langensiepen, Los Angeles, Calif.

Application June 6, 1951, Serial No. 15,439

Term of patent 14 years

(Cl. D9—6)

To all whom it may concern:

Be it known that I, Herman Langensiepen, a citizen of the United States, residing at Los Angeles, in the county of Los Angeles and State of California, have invented a new, original, and ornamental Design for Bathtub Safety Mats, of which the following is a specification, reference being had to the accompanying drawing, forming part thereof.

I claim:

The ornamental design for a bathtub safety mat, as shown.

HERMAN LANGENSIEPEN.
